GRILLE UNIT

Raymond M. Becker and Theodore F. Au Claire, Sr.,
Petoskey, Mich., assignors to Permalum Industries,
Inc., Harbor Springs, Mich., a corporation of Michigan

Filed Mar. 12, 1963, Ser. No. 73,937

Term of patent 14 years

(Cl. D54—2)

Fig. 5

FIG. 1 is a perspective view of a grille unit according to the present invention;

FIG. 2 is an elevational view of the grille unit of FIG. 1;

FIG. 3 is a plan view of the grille unit of FIG. 1;

FIG. 4 is a cross-sectional view of the grille unit of FIG. 1, taken along line 4—4 of FIG. 2;

FIG. 5 is a perspective view of a grille unit according to another embodiment of the present invention;

FIG. 6 is an elevational view of the grille unit of FIG. 5;

FIG. 7 is a plan view of the grille unit of FIG. 5; and

FIG. 8 is a cross-sectional view of the grille unit of FIG. 5, taken along line 8—8 of FIG. 6.

We claim:

The ornamental design for a grille unit, substantially as shown and described.
